UNITED STATES PATENT OFFICE.

WILLIAM MILLER, OF BOSTON, MASSACHUSETTS.

LIFE-PRESERVING MATTRESS.

SPECIFICATION forming part of Letters Patent No. 289,122, dated November 27, 1883.

Application filed May 23, 1883. (No model.)

To all whom it may concern:

Be it known that I, WILLIAM MILLER, of Boston, in the county of Suffolk and State of Massachusetts, have invented certain Improvements in Life-Preserving Mattresses, of which the following is a specification.

This invention has for its object to provide an improved mattress adapted for use on navigable vessels, and also as a float for life-saving purposes, whereby certain advantages are secured over life-saving mattresses heretofore made, all of which I will now proceed to describe and claim.

Of the accompanying drawings, forming a part of this specification, Figure 1 represents a top view of my improved mattress, the covering or upholstery being partially removed. Fig. 2 represents a bottom view of the same. Fig. 3 represents a longitudinal section on line $x x$, Fig. 1. Fig. 4 represents a transverse section on line $y y$, Fig. 1. Fig. 5 represents a longitudinal section on line $z z$, Fig. 1. Fig. 6 represents an edge view. Fig. 7 represents a transverse section, showing a different arrangement of the upholstery from that shown in Fig. 4. Fig. 8 represents a modification.

The same letters of reference indicate the same parts in all the figures.

In carrying out my invention I provide, as the basis of my improved mattress, a flexible base or structure, A, composed of a series of hermetically-sealed tubes, $a a$, of rubber or other suitable flexible and water-proof material, connected by intermediate webs or flanges, a' , formed on or firmly secured to said tubes. Said webs or flanges are preferably of the same material as the tubes. Each tube may have independent flanges, as shown in Fig. 8, placed upon and secured to the flanges of the adjacent tubes; or all the tubes and webs or flanges may be made integral. Each tube is hermetically closed, and has no air communication with any other tube. If desired, each tube may have a tube or orifice whereby it may be inflated, such tube or orifice being provided with a suitable cap or stopper. The tubes may be filled with cork shavings or other buoyant material. The tubes preferably extend lengthwise of the mattress, and are at uniform distances apart. I prefer to make about four tubes on a mattress of ordinary width for

one person. The structure thus formed is covered by suitable upholstery material, c, composed of hair, cork cuttings, or other equivalent material, and an inclosing case or tick. 55 The upholstery material is secured to the base or structure A by fastenings e' , passing through the webs or flanges a' , and secured to suitable buttons or enlargements bearing on the outer surfaces of the cover or tick. It will be seen 60 that the connecting-webs a' keep the tubes a in position relatively to each other, so that said tubes cannot become displaced, and also permit the upholstery material to be secured after it is placed in position on the base A, 65 and without danger of penetrating said tubes by the needle or other instrument used in passing the securing threads or cords through from side to side of the mattress. The tubes projecting from the sides of the connecting-webs 70 form protuberances, whereby the operator is enabled to readily locate the connecting-webs and puncture them without danger of puncturing the tubes. To the bottom of the mattress I secure, by any suitable means, longitudinal 75 slats or stiffening-strips e , which, when the mattress is in place in a berth, bear on the frame-work of the berth and assist in supporting the mattress therein. In case the mattress is thrown into the water, said strips stiffen it, 80 so that it will not sag or bend at any point under the weight of a person or persons sitting upon it. The strips e may be connected by transverse strips e' , if desired, to stiffen the mattress crosswise. 85

f represents a vertical socket rigidly attached to one or more of the stiffening-strips at one end or edge of the mattress, and adapted to hold a flag-pole to attract attention when the mattress is afloat. On the edges of the 90 mattress are pockets, loops, or other devices, $g g$, adapted to hold in concealed positions a flag-pole, h , and a paddle, i .

The slats e may be detachably connected to the mattress, so that they may be placed on either side of the same. It is obvious that the mattress may be provided with straps or cords, to be grasped by persons in the water, said straps or cords being arranged in any suitable manner.

The filling portion of the upholstery material may be omitted from the under side of the

webs a' , to leave vacant spaces under said webs and between the tubes a , as shown in Fig. 7, thereby effecting a saving in material and weight. The webs support the filling above them, so that the mattress is sufficiently yielding when made in this form.

I am aware that it is not new to provide a buoyant mattress with stiffening strips and with devices for holding paddles and flag-poles; hence I do not claim these features.

I claim—

1. In a life-saving mattress, a body, A, of rubber or other suitable flexible yielding and water-proof material, composed of alternating 15 hermetically-sealed parallel tubes a and penetrable connecting webs or flanges a' , formed on said tubes, but having no communication with the air-spaces thereof, and serving to receive upholstery-securing devices, combined with 20 upholstery or covering material secured to the body A by fastening devices passing through

said webs or flanges, the latter constituting elastic or yielding supports for the upholstery, and presenting broad continuous penetrable areas to the tool used in inserting said devices, 25 whereby liability of puncturing the tube a by said tool is obviated, as set forth.

2. A mattress composed of a series of substantially parallel hermetically-closed flexible tubes connected by intermediate webs or 30 flanges, and upholstery or covering material applied to the upper side of said tubes and webs, vacant spaces being left between the tubes below said webs, as set forth.

In testimony whereof I have signed my name 35 to this specification, in the presence of two subscribing witnesses, this 18th day of May, 1883.

WILLIAM MILLER.
